AUTOMATIC POCKET CIGARETTE CASE

Filed April 11, 1930

INVENTOR,
Robert Berger,
BY
John Deinard
ATTORNEY

UNITED STATES PATENT OFFICE

ROBERT BERGER, OF PATERSON, NEW JERSEY

AUTOMATIC POCKET CIGARETTE CASE

Application filed April 11, 1930. Serial No. 443,348.

This invention relates to cases for cigarettes and similar elongated articles and it consists in certain improvements in the case set forth in my Letters Patent No. 1,746,023 having for 5 their objects to provide for greater capacity of the device, facilitate the assembly of its parts, and generally increase its efficiency and improve its construction.

In the drawings,

10 Fig. 1 is a plan of the case, open;

Figs. 2, 3, 4 and 5 are sections on lines 2—2, 3—3, 4—4 and 5—5, respectively, Fig. 2 being a section of one section of the case and Fig. 3 a section of both when closed; and

15 Figs. 6, 7 and 8 are perspective views of certain parts.

The case comprises two rectangular containers or sections 1 and 2 which, in the present example, are counterparts of each 20 other, they being hinged together at 3 and each being a shallow box open at the top side thereof on the side which, when the case is closed, faces the other section. Either may be taken as the body of the case and the other 25 as the cover. The contained mechanism of either is mainly the same as that of the other.

Lining two adjoining sides of the section 1 is a tubular housing 5 and lining a third side (at right angles to the hinge) is a tubular 30 housing 6. To the fourth side at 7 is riveted a plate spring 8 whose free end is rebent at 9 and arched. (The plate-spring of one section may carry the latch 10 to engage a keeper 11 on the other to hold the case closed, 12 being a knob for pressing in the spring to 35 release the latch.) At the free end of the spring the fourth side has the ejecting opening 13 closable by the gate 14 the stem of whose knob 15 projects through slots α in said 40 side and the rebend 9 and has a head 14a bearing against the inner face of the latter. Part 9 thus frictionally resists movement of the gate in either direction. On housing 6 is secured a deflector blade 16 which, when the 45 cigarettes are shifted toward the housing, guides the outer end of the leading one into registry with opening 13.

In housing 6 slides the ejector 17 normally repressed by a spring 18 in the housing and 50 having an external knob 17a for sliding it

toward opening 13 to cause ejection of the leading cigarette, as in my said patent. The ejector protrudes inwardly through a slot 6a in the housing 6 (Fig. 5). The adjoining ends of housings 5 and 6 may merge together as one and an angular section 19 of the top wall thereof forms a removable cover; it is normally held in place in the angle of the section and between the abutments formed at 20, engaging under a lip 20a of one of them 55 (Fig. 3), by the overhanging stud 21 but may be removed by lifting one end to clear one abutment and then sliding it out of place.

To hold the cigarettes in a flat row against the bottom of each section of the case a bent 60 plate-spring 22 is pivoted to one side of the section and may engage under a keeper 23 at the other side on swinging it on its pivot, its convex side being downward.

The follower for urging the row of cigarettes toward housing 6 is constructed as follows: It is a blade 24 formed with an elongated head 25 extending perpendicularly to the plane of the blade and joined thereto by neck 26, said head being forked. The head 70 is received in that part of housing 5 which is perpendicular to housing 6 and the neck occupies a longitudinal slot 27 in said housing part, said head and hence the follower as a 75 whole being urged toward housing 6 by a 80 spring 28 contained in housing 5. Ejector 17 when fully retracted is alined with the mentioned part of housing 5, and the head 25 of the follower (which, of course, holds the follower perpendicular to said part in any of its possible positions) is forked to accommodate 85 said ejector at this time (Fig. 1). Thus while the ejector is normally fully retracted so that the end of the nearest cigarette 90 may oppose it the follower can assume a position where the last cigarette is held against housing 6, or fully opposite opening 13. On removal of the cover 19 the follower 95 may if needed be removed.

For holding the follower back when filling a section of the case there is a latch 29. This latch has a hooked end 29a engaged under a plate 30 secured on housing 5 so as to tilt or pivot on the plate (appearing in section in Fig. 3). The latch is pressed from the hori- 100

zontal wall of the section by a spring 31 so that when the follower is repressed it may be caught and held by the latch. The two latches are opposite each other. Therefore, when 5 the case is closed, if the latches have been made to lock back the followers they will by contact with each other be moved to release the followers, so that the latter press the cigarettes, now held clamped by plate-spring 22, 10 toward wall 6, so that as the cigarettes are one by one ejected from opening 13 they are moved toward said wall.

Having thus fully described my invention, what I claim is:

- 15 1. In combination, a container to hold a row of elongated articles having a bottom and upstanding marginal walls, means to urge the articles toward one wall transversely of them, one wall adjoining the first-named 20 wall having near the latter an ejection opening, means to hold the articles against the bottom, a sliding gate for said opening slideable on the second wall into and out of closing relation to the opening and having a 25 knob device, and a plate-spring attached to the inside of the second wall and having an arched portion, said second wall having a slot extending lengthwise of the movement of the gate and said knob-device penetrating said 30 slot and having wiping contact with said arched portion.
2. In combination, a container to hold a row of elongated articles having a bottom and upstanding marginal walls and two tubular 35 housings extending lengthwise of and arranged respectively inward of two of the walls which adjoin each other, one such housing being longitudinally slotted at the inside thereof and to its end which adjoins the other 40 housing, an ejector movable lengthwise of and in the first housing and protruding inwardly through its slot and normally spring-held in alinement with the other housing, said other housing being also longitudinally 45 slotted, and a follower for the articles spring-held toward the first housing and protruding through the slot of the second housing and having a head within the latter, said head being forked and adapted to receive in its 50 fork the protruding portion of the follower when the ejector is alined with the second housing and the follower adjoins the first housing.
3. In combination, a container to hold a 55 row of elongated articles having a bottom and upstanding marginal walls and two tubular housings extending lengthwise of and arranged respectively inward of two of the walls which adjoin each other, one such housing being longitudinally slotted at the inside thereof and to its end which adjoins the other housing, an ejector movable lengthwise of and in the first housing and protruding inwardly through its slot and normally spring-held in alinement with the other housing,

said other housing being also longitudinally slotted, a follower for the articles spring-held toward the first housing and protruding through the slot of the second housing and having a head within the latter, said head 70 being forked and adapted to receive in its fork the protruding portion of the follower when the ejector is alined with the second housing and the follower adjoins the first housing, and said housing having adjoining 75 portions of their top walls removed and thereby forming an opening through which the follower may be removed, and a removable cover for said opening.

In testimony whereof I affix my signature. 80
ROBERT BERGER.
